[57] CLAIM

The ornamental design for a cap, as shown and described.

DESCRIPTION

FIG. 1 is a top perspective view of a first embodiment of a cap, showing the new design.

FIG. 2 is a top view thereof.

FIG. 3 is a bottom view thereof.

FIG. 4 is a front view thereof. The rear elevational view is the same as the front elevational view; and,

FIG. 5 is a perspective view of the bottom of the cap in an inverted position relative to FIGS. 1-4.

The fragmentary solid black shading shown in the Figures is provided to indicate that the cap is colored black. The broken lines that are illustrated in the drawings form no part of the claimed design.
